JOHN HAYS HAMMOND, JR., OF GLOUCESTER, MASSACHUSETTS

METHOD OF AND APPARATUS FOR SYNCHRONIZATION

Application filed May 22, 1929, Serial No. 364,975. Renewed January 8, 1931.

The object of this invention is to provide a method and apparatus for synchronizing a receiver for television or picture transmission by means of impulses sent from a transmitter for cooperating therewith.

More in particular, the object of this invention is to produce synchronization of a receiver for television or picture transmission by means of picture elements symmetrically arranged relative to the picture it is desired to transmit.

Other objects will become apparent from the following specification taken in connection with the appended drawings.

15 The system embodying this invention uses synchronizing impulses which may be projected as a frame around the picture, so that it is not necessary to use a separate channel for synchronizing. The impulses used for synchronization need not necessarily be separated out from the picture.

Other systems having a similar purpose have not been successful because of the lack of selective features of the synchronizing channel, that is, lack of ability to choose the proper impulses to operate the synchronizing mechanism. The present system, however, provides a selective type of pattern by which the synchronization elements of the picture may be readily and accurately differentiated from the other elements of the picture not intended to influence the synchronization.

In one embodiment of the invention, a frame is made up of the picture elements in such a manner as to give an accurate time interval between the successive impulses which make up the frame. Thus the frame may take the form of a double row of dots surrounding the picture on all sides. When the central portion of the picture and the frame thus provided is being scanned, between the upper and the lower frames, there will occur four dots in sequence, namely two dots at the end of the right border or end of one line and two dots at the beginning or left border of the succeeding line. The time interval between the successive dots should be equal. At the top and bottom of the picture, the number of dots will be much greater as

the four lines of dots follow in succession, that is the two lines of dots at the bottom of the picture and the two lines at the top of the next picture and also the two dots at the right border of the next preceding line and the two dots at the left border of the next succeeding line. In this case also the time interval between all of the dots will be the same although the dots are at widely separated parts of the picture.

As an illustrative example, with 12 dots to a line and 24 lines to a picture, and with a speed of transmission of 15 pictures per second, the time interval between the successive dots will be 1/4320 seconds even if one dot corresponds to the end of one picture and the next corresponds to the beginning of the next picture. The occurrence of picture elements at the rate of 4320 impulses per second indicates that these dots are intended for synchronization. The occurrence of a sequence of four such elements indicates the ending of one line and beginning of the next, with the exact transition occurring in the middle of the sequence. Such sequences occur at line frequency of 360 sequences per second, but a sequence of 52 dots indicates the end of one picture and the beginning of the next, with the transition at the middle of the sequence, and such sequences would occur 15 times per second. In other words, three selective timings by means of the frame elements are provided; first, the regular spacings of dots which serves to differentiate the portion of the picture to be used for synchronization from all other portions of the picture; second, groups of a few dots occurring at line frequency which are used for the lateral framing; and, third, groups of a large number of dots at picture frequency to be used for vertical framing. These dots may be transmitted by using a suitable background for the objects being televised or by use of special holes or other accurately timed devices at a portion of the transmitter scanner not being used for picture pick-up.

Utilization of the framing dots may involve tuning to the dot frequency to select out the synchronizing elements, followed by detection to produce a current of line fre-

quency to control the lateral framing, and a current of picture frequency to control the vertical framing. The driving mechanism for the receiver scanner may be arranged to generate currents having similar frequencies and by matching the locally generated currents against the incoming currents a correcting impulse may be supplied to the driving motor for thus automatically maintaining the frame.

Having thus briefly described my invention, attention is invited to the accompanying drawings in which:

Fig. 1 is a picture or scene adapted to be transmitted and supplied with the framing elements or dots; and,

Fig. 2 represents the circuit for accomplishing the synchronism in accordance with my invention.

Referring now more particularly to Fig. 1, a picture is shown which is composed of the scene to be transmitted and the framing dots. As above described and here illustrated, this picture may consist of 12 dots to a line and 24 lines to a picture and if the pictures are sent at the rate of 15 pictures per second, the successive dots occurring in the upper and lower margin would be transmitted at the rate of 4320 impulses per second.

Referring now more particularly to Fig. 2, 1 represents a radio receiver and amplifier of the usual type for picking up the transmission of the transmitter, and 2 represents an amplifier for supplying the picture impulses to the light adapted to be controlled thereby. The remainder of the circuit represents the apparatus for synchronizing the scanning of the light controlled by the amplifier 2 in reconstructing the picture transmitted. In accomplishing this, the inductance 3 is arranged in parallel with the input of the amplifier 2 in the output circuit of the receiver and amplifier 1. This inductance is inductively coupled to a tuned circuit 4 which is tuned to the dot frequency and therefore is adapted to transfer only energy of said frequency and to reject energy of the heterogeneous frequencies composing the picture part of the transmission. The energy picked up by the circuit 4 is adapted to be detected by the detector 5 and its associated circuits. In the output of the detector 5 there is a tuned circuit 6 which is tuned to the line frequency or the frequency with which the succession of four dots will occur in the transmission, viz., the two at the right end of one line and the two at the left end of the succeeding line. Also in the output of the detector 5 is the oscillatory circuit 7 which is tuned to the picture frequency of, say, 15 per second.

Inductively related to the inductance of the circuit 6 is an inductance connected to the armature exciting coil of the polarized relay 8 and inductively related to the inductance of

the oscillatory circuit 7 is an inductance connected to the armature exciting coil of the polarized relay 9.

The motor 10 is for driving the recording apparatus or the scanning disk 13, as shown, mounted on the same shaft with the motor 10 and the generators 11 and 12. The generator 11 is adapted to generate a frequency which is the same as the line frequency being transmitted, provided the speed of the motor 10 is correct. The generator 12 is adapted to generate a frequency which is the same as the picture frequency provided the speed of the motor 10 is correct. The output of the generator 11 is supplied to the field coil 14 of the polarized relay 8 and the output of the generator 12 is supplied to the field coil 15 of the polarized relay 9. The current for supplying the motor 10 is supplied through the lines 24 through varying combinations of the resistances 20, 21, 22, and 23, as operated to be cut in and out by the relays 16, 17, 18, and 19, respectively.

Relay 16 is adapted to be operated by the polarized relay 8 when the latter is in the right-hand position. Operation of this relay serves to cause the resistance 20 to be included in the circuit of the motor 10.

The relay 17 is adapted to be excited when the polarized relay 8 is in the left-hand position and is adapted to cause the resistance 21 to be removed or short circuited from the circuit of motor 10.

The relay 18 is adapted to be excited by the polarized relay 9 when it is in the right-hand position and is adapted, when excited, to insert the resistance 22 in the circuit of the motor 10.

The relay 19 is adapted to be excited when the polarized relay 9 is in the left-hand position and is adapted to remove the resistance 23 from the circuit of the motor 10.

Thus, when both relays 8 and 9 are to the right, and both relays 16 and 18 are excited, all of the resistances are in the motor circuit. When, on the other hand, both relays 8 and 9 are to the left, relays 17 and 19 are excited and there is no resistance in the motor circuit. When each of the relays 8 and 9 are in neutral, none of the relays 16-19 are excited and resistances 21 and 23 are included in the motor circuit. This is the normal running position and a supplementary rheostat may be provided in the motor circuit to give the rough adjustment of the proper speed for that condition.

Having thus described my invention, I will now describe its operation. If the motor 10 and generators advance in phase with respect to the received current, the line frequencies and picture frequencies of the received current and the line frequencies and the picture frequencies of the locally generated current will be out of phase, and the polarized relays 8 and 9 will operate to close

the right-hand contacts. This causes resistances 20 and 22 to be included in the motor circuit and serves to slow it down. On the other hand, if the motor 10 gets behind in phase with respect to the transmitting current, the relays 8 and 9 will be moved to the left, causing the resistances 20 and 23, which are normally included in the motor circuit, to be removed therefrom, increasing the speed 10 of the motor until synchronization is obtained.

It is obvious that when the system is first started up, the transmitter and receiver will not be in step, and therefore the relays will 15 be in operation until synchronization is established. Thus the system here shown is automatic not only for maintaining the proper framing, but for obtaining it in the first place. It is obvious that the system may be 20 further elaborated as, for example, making the resistance inserted or extracted from the motor circuit proportional to the phase difference in the incoming and local currents.

The light adapted to be actuated by the 25 amplifier 2 will be caused to operate in accordance with the dots which are meant entirely for framing and it will be necessary to limit the area scanned by the electrically controlled lamp in connection with the scanning disk 13 to the picture part of the transmission by the insertion of some frame between the light source and the observing screen. In the recording of the pictures, either the negative upon which the light is 30 adapted to be impressed may be so small as to only include the picture impulses or the light fluctuations covering the picture impulses or the negative produced by the framing dots may be trimmed or framed out in 35 printing, etc.

Having thus described my invention, it is to be understood that the form is shown and described herein for the purpose of illustration only, and that I am not to be limited by 45 the specific embodiment shown, but by the scope of my invention as set forth and defined in the accompanying claims.

I claim:

1. A framing and synchronizing system 50 which involves producing a pattern of picture elements which will not interfere with the picture, said elements producing a regular series of group impulses, comprising, means for selectively tuning these time elements from the other picture elements, means for detecting and producing currents of group frequencies corresponding to a picture frequency and also corresponding to line frequencies, means for actuating a reproducing device, means for producing a group frequency corresponding to the picture frequency, and means for producing a group frequency corresponding to the line frequency by the rotation of said last mentioned means, means for matching the incoming picture frequencies against the local- 55
- ly generated picture frequencies in such a manner as to control the speed of the actuating means to maintain the received picture being framed. 70
2. The method of synchronization for picture transmission which comprises, transmitting a series of impulses representing the picture to be transmitted and including a pattern producing distinctive frequencies, receiving said transmission, tuning to the distinctive frequencies, detecting said frequencies to produce line frequencies and picture frequencies, locally generating line frequencies and picture frequencies in synchronism with the reproducing rotation, and comparing said locally produced and received line frequencies and said locally produced and received picture frequencies to control the speed of said reproducing rotation. 75
3. A method of transmitting picture signals and framing impulses which comprises transmitting in a line for line manner signals representing the intensity of light and shadow on each elemental area of each line of the picture, transmitting a series of horizontal framing signals at the end of each line of signals representing intensities of light and shadow on the record, and transmitting at the end of the series of signals representing the intensity of light and shadow on all lines of the picture and the signals indicating horizontal framing a series of vertical framing signals each of substantially the same amplitude and duration as the horizontal signals and distinguishable therefrom by the period of duration. 85
4. A method of transmitting picture signals and synchronizing impulses for controlling the position of the picture signals at the receiver which comprises transmitting in a line for line manner signals representing the intensity of light and shadow on each elemental area of each line of the picture, transmitting at the end of each line of signals representing intensities of light and shadow on the record for transmission a series of equal amplitude signals to serve as horizontal synchronizing indications, and transmitting at the end of the series of signals representing the intensity of light and shadow on all lines of the picture and the horizontal synchronizing signals separate series of signals of time duration exceeding the horizontal signals and of amplitude and individual duration substantially equal to each horizontal signal to serve as vertical synchronizing signals. 105
5. In a television system for transmitting signals to represent, when reproduced, an image of an object at a transmitter, the method of transmission which comprises transmitting signals varying in proportion to the intensity of light and shadow on elemental areas of a series of lines into which the subject for transmission is assumed to be divided, transmitting as separated signalling impulses at the end 110
- 125
- 130

of each line of transmission of signal indications of light intensity a series of separated signals for indicating horizontal framing, and transmitting at the end of all of said series of signal indications representing light intensities for each line of the subject for transmission and the horizontal framing indications therefor an additional series of signal indications each of intensity and frequency of interruption corresponding to the horizontal signals but of materially greater duration for indicating vertical framing position of the subject for transmission.

6. In a television system for transmitting signalling indications representing successive light intensities on a subject for transmission and framing indications for indicating the relative position of said light indications, means for transmitting in a line for line manner signal representations corresponding to the varying intensities of light and shadow on each elemental area of the subject for transmission, means for transmitting at the end of each line of light intensity indications of the subject for transmission a plurality of signals each of like time separation for representing horizontal framing, and means for transmitting at the end of a complete series of indications of light intensity and the coordinated horizontal framing indications a relatively long series of signals each of like time separation for indicating vertical framing.

7. In a television system for producing at a receiving system an electro-optical image of a subject at a transmitter wherein signals representing the varying intensities of light and shadow for each elemental area of the subject at the transmitter are separated in a line for line manner by horizontal framing indications and at the end of transmission of a series of picture lines by vertical framing indications, the method of reproducing the picture which comprises producing from the picture signals indications of light and shadow proportionate to the indications of light and shadow on each elemental area of the subject for transmission, causing the signals received at the end of each line of signal indications of light value for the subject at the transmitter to differentially vary and control the horizontal framing of the received light impressions, and causing signals representing the vertical framing to differentially adjust the vertical position of all of the received light indications at the end of a complete series thereof.

8. In a television system for producing at a receiving system an electro-optical image of a subject at a transmitter wherein signals representing the varying intensities of light and shadow for each elemental area of the subject at the transmitter are separated in a line for line manner by horizontal synchronizing indications and at the end of complete transmission of a series of intensity

and horizontal synchronizing signals by vertical framing indications, the method of reproducing the picture which comprises producing from the light controlled signals indications of light and shadow proportionate to the indications of light and shadow on each elemental area of the subject for transmission, causing the signals received at the end of each line of signal indications of light value for the subject at the transmitter to differentially vary and control the horizontal synchronization of the received light impressions, and causing signals representing the vertical synchronizing pulses to differentially adjust the vertical position of all of the received light indications at the end of a complete series thereof.

9. A method for synchronizing picture transmission which comprises transmitting a series of impulses representing varying intensities of light and shadow on elemental areas of a subject at a transmitting point, transmitting distinctive frequencies representing horizontal and vertical framing positions of the subject at the transmitter, receiving said transmitted series of impulses, locally controlling the signal reproduction for producing an electro-optical image of the subject at the transmitter, and differentially controlling the locally controlled signal reproduction for framing the received signals both horizontally and vertically upon variance of the locally controlled reproduction from the rate of transmission of synchronizing impulses.

10. In a system for receiving television images and for synchronizing the same, means for receiving signals indicating light values of elemental areas of a subject at a transmitter and signal indications of distinct frequency representing horizontal and vertical synchronization thereof, means for producing from the signal indications of light values corresponding light values for constructing an electro-optical image of a subject at the transmitting point, means at the receiving point for locally controlling the relative position at which said light values are reproduced at the receiver, means for differentially controlling the position of said light reproduction at the end of each line of received light intensity indications for horizontally synchronizing the received light indications, and means for differentially controlling in response to vertical synchronizing indications the vertical position of the complete series of light indications after a complete series of light intensity indications and horizontal synchronizing indications of the entire subject at the transmitter have been received.

JOHN HAYS HAMMOND, JR.
